UNITED STATES PATENT OFFICE.

SAMUEL F. CLOUSER, OF BROOKLYN, NEW YORK.

RAILWAY SIGNAL APPARATUS.

SPECIFICATION forming part of Letters Patent No. 698,376, dated February 18, 1902.

Application filed March 23, 1899. Renewed July 19, 1901. Serial No. 68,963. (No model.)

To all whom it may concern:

Be it known that I, SAMUEL F. CLOUSER, a citizen of the United States, residing at Brooklyn, in the county of Kings and State of New

5 York, have invented certain new and useful Improvements in Railway Signal Apparatus, of which the following is a full and complete specification, such as will enable those skilled in the art to which it appertains to make and 10 use the same.

This invention relates to signal devices for use on railways, and particularly to that class of signal devices which are designed to signal to the engineer of a train that he is approaching 15 a drawbridge, defective trestle, or other danger-point.

The invention is fully disclosed in the following specification, of which the accompanying drawings form a part, in which—

20 Figure 1 is a plan view of a section of a railway-track and turn-table, showing my improved signal apparatus applied thereto, part of the construction being shown in section; Fig. 2, a side view thereof, part of the construction being in section.

In the drawings forming part of this specification the separate parts of my improvement are designated by numerals of reference, and in said drawings, reference being 30 made to Figs. 1 and 2, I have shown at 5 the rails of a railway-track and at 6 the rails of a drawbridge, the frame of which is shown at 7, and in the practice of my invention I secure or place at a predetermined distance 35 from the drawbridge and adjacent to one of the rails of the track a box or casing 8, in which is pivoted a lever or support 9, provided at one end with an angular arm 10, which is provided at its end with a support 40 11 for a torpedo or other explosive signal device. At equal distances from the pivoted support 12 of the lever 9 is pivoted to said lever, as shown at 13, a rod 14, and the rods 14 pass through tubes 15, which extend along 45 the track, as shown in Fig. 1, and adjacent to the drawbridge is pivoted another lever 16, with the opposite ends of which the rods 14 are pivotally connected, as shown at 17. The lever 16 is provided with an arm 18, having 50 a vertically-arranged pin 19, and secured to the drawbridge or to the side of one of the rails 6 thereof is a bracket 20, provided with

a short arm 21, which projects parallel with the adjacent rail 6, and with a longer arm 22, which projects at an angle of about forty-five 55 degrees to the arm 21.

In the operation of this apparatus the angular arm 10 of the lever 9 is adapted to be thrown over the adjacent rail 5 of the main track to support a torpedo thereover, and 60 said operation will be readily understood from the foregoing description when taken in connection with the accompanying drawings and the following statement thereof. When the drawbridge is in the position shown in Fig. 65 1, there is no danger to an approaching train, and the train will pass thereover in the usual manner; but if at any time the drawbridge be turned, it being understood that this operation is performed in the direction of the 70 arrow shown in Fig. 1, the short arm 21 of the bracket 20 will strike the pin 19 of the arm 18 of the lever 16 and will turn said lever into the position shown in dotted lines in Fig. 1. This operation will also throw the 75 lever 9 into the position shown in dotted lines, and the torpedo-support 11 will be directly over the adjacent rail 5. As the train approaches the torpedo is exploded by the wheels 80 of the engine, and the engineer is thus signaled to the effect that the drawbridge is open, as shown in dotted lines in Fig. 1. When the drawbridge is moved back into the position shown in full lines in Fig. 1, the pin 19 is struck by the arm 22 of the bracket 20, 85 and the operation of the signal apparatus is reversed, the torpedo-support being moved backwardly and away from its position over the adjacent rail 5, as shown in full lines in 90 said figure. It will be understood that a torpedo may be placed on, connected with, or secured to the support 11 in any desired manner.

As shown in the drawings, the angular arm 10 passes through a slot in the side of the 95 casing 8, and the pivot-pin 23 of the lever 16 passes through a bracket-arm 24, secured to a block 25, and the adjacent sleeper 26, and the said lever is mounted between said bracket-arm and said sleeper; but any suitable means for supporting said lever may be employed.

My improvement is simple in construction and operation and well adapted to accom-

plish the result for which it is intended, and it will be apparent that changes in and modifications of the construction described may be made without departing from the spirit of my invention or sacrificing its advantages.

Having fully described my invention, I claim as new and desire to secure by Letters Patent—

1. A railway signal apparatus adapted to be operated by a movable portion of the track mounted on a pivotal support and adapted to turn in a horizontal plane, comprising a support pivoted adjacent to the track at a predetermined distance from said movable portion thereof, said support comprising a lever, one end of which is adapted to be thrown over the adjacent rail of the track, another lever pivotally supported adjacent to the movable portion of the track, said levers being in operative connection at each side of their pivotal supports, and an operating device connected with the movable portion of the track, and provided with two arms or projections, one of which is longer than the other, said arms or projections being adapted to turn said last-named lever in both directions, substantially as shown and described.

2. A railway signal apparatus adapted for use in connection with a movable portion of a track and consisting of a casing arranged adjacent a fixed portion of a track, a lever mounted therein and having one end portion capable of oscillation into a position above said fixed track portion, another lever mounted adjacent said movable track portion and provided with a projecting arm, both of said levers being operatively supported approximately centrally, and the ends of each lever being connected operatively with the ends of the other lever, said movable track portion

being provided with a bracket secured to one of the rails thereof and provided with a shorter arm which approximately parallels said rail, and a longer arm at an angle therewith, which bracket operates in connection with a pin fixed to the arm of said lever which is mounted adjacent said movable track portion, to swing said last-named lever in both directions whereby a torpedo placed upon one end of said lever adjacent the fixed portion of said track, may be swung above and retracted from said fixed track portion, substantially as shown and described.

3. In a railway signal apparatus adapted for use in connection with a movable portion of a track, and comprising a first pivoted member mounted adjacent a fixed portion of a track, and adapted to hold a torpedo and to throw the same over said track portion, and a second pivoted member operatively connected therewith, and mounted adjacent said movable track portion and provided with a pin or stud; a bracket secured to one of the rails of said movable track portion and provided with a short arm which approximately parallels the adjacent track and with a long arm which projects at an angle thereto, said pin or stud being arranged to operate in connection with and between said arms, and to be moved thereby to pivotally move said first member, substantially as shown and described.

In testimony that I claim the foregoing as my invention I have signed my name, in presence of the subscribing witnesses, this 22d day of March, 1899.

SAMUEL F. CLOUSER.
